JOURNAL BOX CLOSURE

William L. Dwyer and Michael J. Healey, Indianapolis, Ind., assignors to Railway Service & Supply Corporation, Indianapolis, Ind., a corporation of Indiana

Application August 5, 1936, Serial No. 94,330

3 Claims. (Cl. 308—47)

This invention relates to closure or cover means for journal boxes such as are used on railway cars and one of the primary objects of the invention is the provision of an improved closure adapted to ensure tight and effective closing of the journal box.

Another object of our invention resides in the provision of improved means in association with a cover or lid of the construction commonly used on journal boxes, which means is adapted to provide a tight seal or closure for the journal box opening under operating conditions such as would cause closures as heretofore constructed to leave the face of the box against which it should seat.

A more specific object of our invention resides in the provision of means for providing an effective seal for journal box openings adapted to be applied to covers of standard construction in a very simple and inexpensive manner.

How the foregoing, together with such other objects and advantages as may appear herein-after or are incident to our invention are realized, is illustrated in preferred form in the accompanying drawing, wherein

Figure 1 is a front view of a railway journal box having a closure embodying our invention applied thereto, certain portions of the view being broken out to show interior construction;

Figure 2 is a cross section taken substantially on the line 2—2 of Figure 1, and

Figure 3 is a fragmentary cross section taken substantially on the line 3—3 of Figure 1.

The invention will be described in connection with journal box constructions now commonly employed on railway cars which comprise, in general, a journal box A having a front opening 4 for the introduction of the journal box packing 4 composed of oil and waste, a cover B adapted to seat on the surface 5 surrounding the opening 4, a hinge pin 6 fitting suitable hinge lugs on the box and cover for pivotally mounting the cover on the box, and spring means such as a torsion spring 7. The lower free ends of the spring 7 are engaged behind a clip 8 secured to the inner face of the cover B and the upper portion 9 of the spring engages a projection 10 on the journal box lug. This construction provides for yieldingly holding the box either in open or closed position in a well known manner.

It is customary to machine the surface 5 of the box but not the inside face of the cover B that comes in contact with it, and since the cover is a rough casting the surface may often be irregular and distorted so that the cover does not

make a good seal. Also the hinge pin hole in the box very seldom lines up with the hole in the cover to let the cover come in proper contact with the box to make a complete seal around the entire surface of the opening. Furthermore, the cover is made heavy to withstand the rough usages of service and, therefore, its inertia is such that vibration keeps it continually bouncing, and while this vibration is depended upon to wear the surfaces of the box and lid into a good contacting surface, the bouncing causes the cover to open slightly and allows the entrance of water and dirt and other foreign matter into the box.

We propose to overcome such difficulties and to provide very effective sealing of the box by means of an improved inner cover or seal arrangement indicated as a whole by the reference letter C and comprising a relatively light cover or lid member 11 mounted on the inside of the main or standard cover B and preferably in the form of a rectangular pan made of sheet metal.

The inner lid is mounted on the cover B by means of two shouldered bolts or studs 12, having heads 13, the bolts or studs being secured in the cover by means of castellated nuts 14. Before securing the bolts in place they are passed through holes 15 in the lid 11 which are slightly larger in diameter than the diameter of the portions 16 of the bolts. Compression springs 17 are slipped onto the bolts and then a centering and equalizing bar 18 having holes 19 through which the bolts pass is put in place and the bolts are then secured to the outer cover. The bolts act as guides for the inner lid and keep it lined up with the opening in the box.

The holes 19 in the bar are sufficiently larger in diameter than the portions 16 of the bolts to enable the bar to rock on a centrally located bearing member or rivet 20 secured in the bar and having a rounded head which contacts the inside face of the outer cover B.

It will be seen from the foregoing that the inner lid is spring mounted on the outer cover and that when the cover is open the compression springs push the inner lid against the heads 13 of the bolts which act as stops. The mounting and bar arrangement is such that the inner lid can move toward and away from the outer cover in parallel relation thereto and also so that it can be tilted in all directions with the rivet 20 of the bar 18 as a fulcrum. Thus the inner lid will accommodate itself to the surface 5 of the box and make a tight seal even if the relation of this surface to the inner face of the outside cover were such that the cover would not rest flat on its seat. For

example, if the condition were such that the inner lid would first contact with the surface 5 at only one point or along only one edge of the box opening, then the compression springs would yield and the bar 18 would rock on its pivot until a complete seal were made all the way around the opening. Under such a condition the outer cover would not seat flat on the inner cover, but since the inner cover provides the seal for the opening any foreign matter which might pass the outer cover would not be able to pass into the box. In other words, the arrangement is such that the inner or sealing lid is forced flat onto the surface 5 of the box before the outer cover comes into contact with the flange 21 of the inner lid, thus ensuring an effective and complete contact. Since the inner lid is made of sheet metal the flange 21 which extends completely around the lid is smooth and free from distortion so that a good seating surface is provided. I prefer to line the seating face of the flange with a gasket 22 preferably of oil resistant rubber or similar resilient material which may be vulcanized in place. This provides a yieldable seat and further ensures a tight seal.

It is also pointed out that due to the lightness of the inner lid 11 it has considerably less inertia than the outer cover B and since it is held in place by the reaction of the compression springs 17 between it and the heavier cover, it is maintained in a closed or sealing position even though the outer cover may vibrate in service when the railway car passes over rail joints, switches, crossings and the like, so that objectionable substances cannot enter the journal box to destroy the lubricant for the journal and bearing.

The lower portion 23 of the inner lid is disposed at an angle or tapered so that any water, dirt or other foreign matter which may collect in the pan portion of the lid due to vibration of the outer cover or to irregularities in its shape may be readily drained or removed by opening the cover.

By means of our invention a journal box closure is provided in which there is a double spring action for maintaining an effective seal, i. e., the main closure spring 7 acts to urge the outer lid toward the seat and the spring mounting arrangement of the inner lid acts to seat the inner lid properly on the box. Also in the case of jolts which tend to unseat the cover, the spring 7 reacts from the box to offer resistance and the

springs 17 react from the outer cover to maintain the inner lid in sealing position so that the combined action of these spring devices prevents unseating of the closure. In addition the gasket 22 because of its yieldable nature, aids in maintaining the seal. 5

We claim:

1. In combination with a journal box having a front opening, pivoted cover means for said opening, and spring means for spring closing 10 said cover means, said cover means comprising an outer lid, an inner lid having a surface adapted to seat on the periphery of the box opening, spaced studs secured in the outer lid for mounting the inner lid on the outer lid, a bar loosely 15 fitting said studs and located between the inner and outer lids, compression springs between the bar and the inner lid, a center bearing for the bar having contact with the inside of the outer lid, and means on said studs limiting movement 20 of the inner lid in a direction away from the outer lid under action of said compression springs.

2. In combination with a journal box having a front opening, pivoted cover means for said 25 opening, and spring means for spring closing said cover means, said cover means comprising an outer lid, an inner lid having a surface adapted to seat on the periphery of the box opening, and means for yieldingly mounting said inner lid 30 on the inside of said outer lid for movement toward and away from the outer lid in parallel relation thereto and for tilting movement with respect to the outer lid including an equalizer bar and springs between said bar and said inner lid. 35

3. In combination with a journal box having a front opening, pivoted cover means for said opening, and spring means for spring closing 40 said cover means, said cover means comprising an outer lid, an inner lid having a surface adapted to seat on the periphery of the box opening, and means for yieldingly mounting said inner lid on the inside of said outer lid comprising members secured to the outer lid for guiding the 45 inner lid, a bar centrally fulcrumed on the inner face of the outer lid, and compression springs between the free end portions of said bar and the inner lid.
